UNITED STATES PATENT OFFICE.

ROBERT WOOD, OF NEW YORK, N. Y.

VACUUM-BREAKER.

1,391,600.

Specification of Letters Patent. Patented Sept. 20, 1921.

Application filed June 2, 1915, Serial No. 31,641. Renewed February 12, 1921. Serial No. 444,535.

To all whom it may concern:

Be it known that I, ROBERT WOOD, a subject of the King of England, and resident of New York city, in the county of Kings and State of New York, have invented certain new and useful Improvements in Vacuum-Breakers, of which the following is a specification.

My invention relates to vacuum breakers or relief valves for steam engine cylinders, particularly locomotive cylinders, and it has for its object to provide a device of this character which will operate automatically to supply a predetermined low steam pressure to the cylinder and prevent the formation of a partial vacuum in the cylinder when the steam supply is cut off or reduced below a certain point.

In a locomotive the exhaust from the cylinders is usually connected to the smoke stack to furnish a suction draft for the fire box when desired, and therefore if a suction is developed in the cylinder it may draw cinders, dust, etc., through the exhaust ports into the cylinder to score the piston and the cylinder walls. To prevent this entirely the device must operate to prevent the formation of a partial vacuum rather than be operated by a partial vacuum.

With low pressure locomotive it has been customary to equip each cylinder or steam chest with a puppet valve adapted to open and admit air in response to a suction in the cylinder, but this form of relief valve is objectionable with any locomotive because dirt is liable to enter the cylinder even though the entrance is screened. For a superheated steam locomotive this form of valve has the further objection that the admission of cold air to the cylinders causes a deposit of carbon to form on the piston and the cylinder walls. Finally, this form of valve is objectionable because it interferes with modern lubrication methods.

By my invention I automatically furnish a predetermined supply of steam to the cylinder when the throttle is closed and before any objectionable vacuum can be created in the cylinder. Furthermore, I automatically maintain this pressure between certain predetermined limits as long as the throttle remains closed with the engine in service.

Broadly considered, my invention consists of a valve controlling a passage from the boiler to one or both of the cylinders, which passage is independent of the throttle, and

means for opening said valve by the steam pressure from the boiler whenever the pressure in the cylinder falls below a certain point and before any vacuum is created in the cylinder.

More specifically, it consists of a differential piston valve controlling this independent passage from the boiler to the cylinder, the small area end of the piston valve being always exposed to the full boiler pressure, and the large area end of the piston valve being always exposed to the pressure in the cylinder, so that by proportioning the relative areas of the two ends of the differential piston valve it may be given an automatic movement to admit steam from the independent passage to the cylinder or cylinders whenever and as soon as the pressure in the cylinder falls below a given point.

Referring to the accompanying drawings:

Figure 1 is a diagrammatic outline view of one side of a locomotive showing a preferred embodiment of my invention mounted in operative position on one side thereof, and

Fig. 2 is an enlarged central vertical sectional view taken through the device shown in side elevation in Fig. 1.

In the following description and in the claims, parts will be identified by specific names for convenience of expression, but they are intended to be as generic in their application to similar parts as the art will permit.

In the drawings there is shown a locomotive 3, provided with a steam chest and cylinder 4 and piston rod 5 actuated by steam admitted to the chest and controlled by a throttle valve in the engineer's cabin as is usual with devices of this character.

Mounted on one side of the locomotive relatively close to the steam chest is a vacuum breaker 6 in the form of a tubular block or casing, provided with an attaching plate 7, preferably formed of an integral casting.

Within this casing is a pair of tandem concentric cylinders 8 and 9, the latter being relatively larger in diameter than the former. The outer end of the larger cylinder is closed by a cylinder head or cap 10, and the inner end of the larger cylinder is in free communication with the adjacent end of the smaller cylinder. The opposite end of the smaller cylinder is connected by

means of a pipe 11 with the locomotive boiler.

Within the cylinder 8 there is a snug fitting piston 12, and within the large cylinder 9 there is a snug fitting piston 13. These two pistons may be integral, but for the purpose of avoiding the necessity of accurately lining up the walls of the two cylinders relatively to each other, I prefer to make them separate.

At the head end of the cylinder 9 there is a port 14 communicating through a passage-way or space 14', and pipe 15 with the steam chest or main steam inlet pipe 16. The cylinder head 10 is arranged to act as a stop to prevent the large piston 13 from closing the port 14, and in order to maintain the piston area substantially the same when it is in contact with the stop as it is when moved away from the stop, the cylinder head is brought down to a cylindrical knife edge 17, and ports 18 through the head admit steam pressure to the portion of the piston inclosed within the knife edge when the piston is in contact therewith. Obviously the same result may be accomplished by breaks in the knife edge to constitute the ports.

It will be observed that by this arrangement I have a differential piston in which the small area piston is always subject to boiler pressure, while the large area piston is always subject to steam chest pressure.

If, therefore, we assume that the areas of these pistons are as ten to one, it will be seen that at all times when the steam chest pressure exceeds one-tenth of the boiler pressure, both pistons will be forced to their extreme position away from the stop, but that whenever the steam chest pressure drops below one-tenth of the boiler pressure, the pistons will be moved into the position shown in Fig. 2 with the large piston forced against the stop.

In the small cylinder there is a port 19 adapted to be uncovered when the pistons are in the position shown in the drawing, and to be closed when the pistons are at or near their other extreme position. The port 19 communicates through a pipe 20 with the steam chest or main steam inlet 16. Obviously, therefore, if the pistons are in the position shown in the drawing, boiler pressure from the pipe 11 passes through the port 19 and the pipe 20 to the main steam inlet.

Inasmuch as these pistons are not provided with rings or packing of any kind, it would be possible for the steam to leak by the piston into the cylinder space between the two pistons, and to avoid the accumulation of pressure in this space, I provide drip passages 21, 22 and 23. The passages 21 and 22 are both in the large cylinder, and are designed to be covered successively by the

large piston as it moves away from the stop. While one of these drip passages would be sufficient for the purpose, I prefer to provide two or more, as they permit the utilization of an air cushion having a tendency to prevent the large piston from being driven forcibly against the inner end of the cylinder by sudden accumulation of pressure through the port 19.

As a further cushion for the large piston, I provide a coil spring 24. It will be noted that the spring 24 also tends to maintain the valve 12 in position to permit the flow from pipe 11 into pipe 20 through port 19. The drip 23 serves to prevent the accumulation of pressure due to leakage when the drips 21 and 22 are closed by the large piston, and to increase its facility of action I may provide a groove 25 in the small piston adapted to register with the drip 23 when the pistons are in their extreme position away from the stop.

The operation of my device is as follows: When the engine is running under pressure the small piston is subject to the boiler pressure of say two hundred pounds through the pipe 11. The large piston is subject to substantially the same pressure through the pipe 15 and the port 14. This will cause the differential piston to move to its extreme position away from the stop, and consequently the small piston will close the port 19.

If, however, the engineer closes his throttle, the steam pressure in the main inlet pipe 16 and in the steam chest will rapidly fall, and this will cause substantially the same drop in pressure in the pipe 15 and the port 14. Again assuming that the piston areas are as ten to one, the position of the piston will remain unchanged until the steam chest pressure drops below twenty pounds. The result will be that the constant or boiler pressure on the small piston will overcome the pressure on the large piston, and the differential piston will move toward its stop to open the port 19.

As soon as the port 19 is open, the constant or boiler pressure is admitted to the pipe 20, and thence to the main steam inlet and steam chest, whereupon the pressure upon the large piston will rapidly rise. As soon as this pressure rises above twenty pounds, the differential piston will move back to close the port 19, and thereby prevent the pressure from exceeding the predetermined amount. As long, therefore, as the throttle remains closed, this differential piston will float back and forth to maintain a pressure of substantially twenty pounds in the steam chest, thereby preventing the formation of a partial vacuum in the cylinder.

It is customary in locomotives to branch the main steam line to the steam chests on each side of the cylinder, and therefore when

steam pressure is admitted through the port 19 and the pipe 20 to the branch shown in Fig. 1, it will find its way to the branch of the steam chest on the other side of the locomotive, but it may be preferable in some cases to make a separate port 19^a and a pipe 20^a communicating directly with the branch of the steam chest on the other side of the locomotive.

- 10 When the locomotive is coasting, the differential piston floats back and forth to maintain the steam pressure in the steam chest within the desired limits, but when the locomotive is standing still with the 15 throttle necessarily tight shut, the differential piston will remain in position away from the stop. Under these circumstances, the provision of drip passages is important, because there might be a gradual accumulation 20 of pressure in the steam chest and in the cylinder due to leakage past the differential piston which will eventually be sufficient to start the locomotive. For ordinary purposes I have found that the provision 25 of the drips is sufficient, but as an extra precaution I may provide a valve in the pipe 11 to be closed when the engine goes into the round house, or whenever it is desirable.
- 30 It will be observed that by this construction I prevent the formation of a vacuum in the cylinder when the throttle is closed, furnish steam to carry on lubrication, and avoid the admission of cold air to the cylinder. It will also be observed that the 35 device works automatically whenever the pipe 20 is connected with the boiler.

In using the term cylinder in the claim, I

wish to be understood as including the steam chest and the steam inlet.

Having thus described my invention, I claim:

In a device of the class described, a casing provided with a bore extending therethrough from end to end and substantially closed from the external atmosphere, one end of said bore being enlarged to form the same into a large chamber and a relatively small chamber, the end of the bore at the small chamber constituting an opening from a source of relatively high pressure, said casing provided with an outlet port leading from the small chamber and adapted to communicate with a space designed normally to have a high working pressure therein, a relatively small piston having a sliding fit in the small chamber and projecting therefrom into the large chamber, said outlet port controlled by said small piston, a relatively large piston having a sliding fit in the large chamber, said pistons coacting to constitute a two-part differential piston, a spring acting on the small piston for maintaining the same in bearing engagement with the large piston and for moving said small piston into position uncovering said outlet port, said large chamber provided with a port for placing the large end of the differential piston continuously in open communication with said high pressure space and a stop cap for the large end of the bore.

Signed at New York, in the county of New York, and State of New York, this 27th day of May, A. D. 1915.

ROBERT WOOD.
